UNITED STATES PATENT OFFICE.

JOHAN PETER HEMME LUND, OF ROCKHAMPTON, QUEENSLAND, AUSTRALIA.

RUDDER FOR CONTROLLING THE VARIOUS MOVEMENTS OF SCREW-PROPELLED VESSELS AND MEANS FOR OPERATING SAME.

947,833.

Specification of Letters Patent.

Patented Feb. 1, 1910.

Application filed January 22, 1908. Serial No. 472,904.

To all whom it may concern:

Be it known that I, JOHAN PETER HEMME Lund, citizen of Australia, residing at The Waterworks, Rockhampton, in the State of Queensland, Australia, engineer, have invented new and useful Improvements in Rudders for Controlling the Various Movements of Screw-Propelled Vessels and Means for Operating Same, of which the following is a specification.

This invention relates to an improved construction of folding rudders and means for operating same, by which the movements of screw propelled vessels, fitted therewith, are completely under the control of the helmsman or navigator of such vessel, and providing that the propeller is revolving at an effective speed in the proper direction, he, the helmsman or navigator, can, from his place on the vessel, and without the main engines or motive power being in any way manipulated, cause the vessel to conform to any and all of the usual maneuvers of a screw propelled vessel, namely, to go ahead at any desired speed, within the maximum, to stop, or to go astern at a more or less moderate rate of speed, and at the same time to answer the helm in the usual manner. In addition, he can also turn the vessel in its own length, in either direction and without any substantial forward or backward movement through the water. The vessel, is, therefore, under better and surer control, especially in confined waters; collisions are more easily avoided; and, if desirable, the engine or motive power with the propeller rigidly attached, may be started while the vessel itself remains stationary and unaffected, although ready for any movement which the helmsman or navigator may desire to make.

My improved construction of folding rudder, provides the maximum strength with the minimum cross-sectional area and obstruction, the vertical joint is close, and when the rudder is in either its neutral or go astern position, water cannot escape astern and destroy its efficiency, while the construction of the operating device is simple and effective, and it contains no features liable to disorder. The engines in a vessel fitted with it, may be of the simplest kind, and constructed for going ahead only, and, as the propeller is never disconnected or in any other way relieved of its resistance, (ex-

cept, if desired, in starting the engines), no throttling mechanism need be provided, and, in the case of engines not readily reversed, such as oil, gas, or turbine engines, the usual reversing gear, disengaging clutches, reversing propeller etc., may be entirely dispensed with, thereby effecting a saving in cost, which will more than compensate for the additional cost of installing my improved folding rudder and means for operating it.

Briefly stated, my invention consists in an improved construction of folding rudder and means for operating it, so that it is enabled to deflect, retard or reverse the current of water sent astern by the action of the propeller, whereby, in turn, the control of the vessel, as already described, is brought about. This opening, closing, and turning of my improved folding rudder is performed and controlled by the helmsman or navigator from his usual position on the vessel, and is transmitted to the rudder by suitable mechanical means, either by hand power, steam, oil, gas, hydraulics, electricity, compressed air, or whichever motive power may be considered most suitable and convenient, according to the size and equipment and requirements of the vessel. Means are also provided whereby the relative position of the blades of the rudder may be indicated to the helmsman or navigator.

In order that my invention may be clearly understood, I will now more fully describe it by the aid of the accompanying drawings, in which my improved folding rudder and its actuating mechanism is shown, as suitable for small or moderate sized vessels.

Figure 1 is a side elevation, partly in section, the rudder being in its closed or "go ahead" position; Fig. 2 is a plan view of the same; Fig. 3 is a plan showing the rudder opened approximately to its neutral or "stop" position; Fig. 4 is a plan, partly broken away, showing the rudder opened to its fullest extent or in the "go astern" position; Fig. 5 is a side elevation of a combined steering and controlling device; Fig. 6 is an elevation of the rudder blades, with their respective shank and sleeve, or rudder heads, separated; and, Fig. 7 is a sectional plan of the blades.

Referring to the drawings, it will be seen that the rudder is vertically divided or split into two halves or blades A and B, which are pivoted on a common axle. These

blades may, preferably be in the shape of a semicircle and when fully opened must form a disk somewhat larger in diameter than the propeller and concentric with it. The one-half A has a rudder head in the form of a shank A', while the other B has a rudder head in the form of a sleeve B', the former being an easy fit in the latter.

In carrying out my improved construction of the folding rudder, I forge or cast, as the nature of the metal may require, arms or fins A² B² on the shank A' and the sleeve B', respectively, and to these arms or fins A² B², are riveted on either side thereof, the blades A, B, and dished or stiffening plates A³ B³ which latter are also, at their outer edges, riveted to their respective blades. The sleeve B' and, with it, the shank A', are carried at their upper ends by the bushing C, and they project sufficiently to allow of the tiller and operating levers or cranks hereinafter described to be attached. When the shank A' and the sleeve B' pass through the center D of the vessel a trunk C' is fitted to prevent the ingress of water. The lower end of the shank A' may be supported in the footstep bearing E, carried on the heel or sole piece, or the whole may be supported by judgements or straps from the stern post, in the usual manner. On the upper end of the shank A' and sleeve B' the bifurcated ends of the tiller F are loosely fitted and between the jaws F' thereof, the levers G and G' are rigidly attached to the shank A' and the sleeve B' respectively.

The tiller F is made hollow for nearly the full length thereof, and in it, and supported in bearings at each end, with a ball thrust bearing at the outer end, works a screw H, which carries a traversing nut K having lugs extending on either side through longitudinal slots F², formed for the purpose in each side of the hollow tiller. The extensions or lugs on the nut K are connected to the before mentioned levers G and G' by means of the connecting rods or pitmen L and L', respectively. The central operating screw H has a spindle H' which extends through the end of the tiller and carries a gipsy or chain driven wheel J, from which the chain N, is carried over either of the leads M, to either of the leads M' which latter are central with the rudder head, and, therefore, unaffected by the movements of the tiller; and thence, over other suitably placed leads to the gipsy or chain driving wheel S, of the controlling gear, Fig. 5, at the hands of the helmsman or navigator, and back to the place of starting. In its simplest form, this controlling gear, Fig. 5, may be mounted independently on the same spindle which carries the steering wheel P, and drum Q, and consists of a hand wheel R, to which is attached the gipsy or chain

driving wheel S, from which the usual chain may be carried by suitably fixed leads to the before-mentioned driven chain wheel J, on the tiller F. The steering ropes or chains are carried independently from the steering wheel drum to the tiller, over suitable leads, in the usual manner.

In order that the helmsman or navigator may at all times, and without leaving his post, be aware of the relative position of the two blades forming the rudder, a dial and pointer indicating these positions and operated by the hand wheel R by worm and worm wheel or other suitable gearing, may be placed in a convenient position for observation and, in addition, if desired, the various positions of the blades of the rudder may also be indicated by the sounding of a gong.

Having thus fully described, and with drawings illustrated the details of my invention, I will now proceed to describe its application and the manner in which the vessel is controlled by it. With the two blades A, B, of the rudder closed, or in the position shown in Figs. 1 and 2, the engines being started, the vessel will move ahead, and will steer in the usual manner. Should it now be desired to reduce the speed of the vessel, it will not be necessary to throttle or slow down the engines; the helmsman or navigator will simply turn the hand wheel R, under his control, in the desired direction, when the chain wheel J, and, with it, the screw H will, actuated by the chain N, be rotated, and thus cause the nut K to travel along the tiller F and through the medium of the connecting rods or pitmen L L', levers G G', and shank A' and sleeve B', will cause the blades A, B, of the rudder to open. This movement will gradually cause the stream of water thrown astern by the propeller to be divided and deflected to either side, and the speed of the vessel will be correspondingly decreased until a position approximating to that shown in Fig. 3 has been reached, when the deflection of said stream of water has become so great, as to impart no forward movement to the vessel, which, consequently comes to a standstill. If the hand wheel R be further rotated until the blades of the rudder occupy the position shown in Fig. 4, then, the force of the water thrown against the opposing blades of the rudder, together with its reaction on the surrounding water, will be sufficient to move the vessel astern at a moderate speed and by the aid of the helm it may be steered, as desired. In either of the latter positions of the blades of the rudder, Figs. 3 and 4, and with the helm hard aport or starboard, the vessel may be smartly turned, within its own length, in either direction, and a correspondingly less turning movement may be obtained with the blades at any lesser degree.

of opening, always provided that the propeller is constantly at work. When a vessel is lying at its moorings, or alongside a jetty, it is often desirable to try the engines before starting, and with my improved construction of folding rudder and operating gear installed, this may be readily accomplished without inconvenience or strain, by simply placing the rudder in its neutral or stop position. The engines may then be started and run until everything is in perfect readiness for a final start, which, as already described, is gradually effected by the closing of the rudder to its normal position. Figs. 1 and 2.

I have, in this description described my invention in its simplest form. It will be understood, however, that the details of construction may be varied according to circumstances and the size of the vessel to which it is to be fitted. For instance, the screw H and the tiller F may be actuated by any known motive power or from the main engines or the screw may be substituted by direct pressure from a hydraulic ram, such mechanism being controlled by suitable devices by the helmsman, or navigator.

Having now particularly described and ascertained the nature of my said invention and in what manner the same is performed, I declare, that what I claim is:

1. The improved construction of folding rudder and mechanism for operating same, consisting of a tiller loosely carried on but indirectly connected to the shank and sleeve of such rudder; a screw carried in such tiller, and provided with a driving wheel; and a traversing nut; rods connecting such nut with levers rigidly attached to the shank and sleeve respectively; as and for the purposes herein set forth and described, and as illustrated by the accompanying drawings.

2. In an improved construction of folding rudder and mechanism for operating the same; consisting of a tiller loosely carried on, but indirectly connected to the shank and sleeve of such rudder; a screw carried in such tiller, and provided with a driving wheel and a traversing nut; rods connecting such nut with levers rigidly attached to the shank and sleeve, respectively; in combination with means for operating or controlling the same from any suitable position on the vessel, consisting of a hand wheel, carrying a chain driving wheel, and a driving chain; as and for the purposes herein set forth, and described, and illustrated by the accompanying drawings.

3. In a screw propelled vessel, the combination of a pair of blades forming a rudder;

means by which said blades can be turned to either side, opened out one from the other, or closed together, comprising a shank and a sleeve for carrying said blades; a tiller loosely carried on, but indirectly connected to said shank and sleeve; a screw carried in such tiller and provided with a driving wheel and a traversing nut; connections between said nut and said shank and sleeve; and means for operating said tiller from any suitable position on the vessel, comprising a hand wheel and a chain driving wheel, substantially as described.

4. An improved rudder for controlling the various movements of screw propelled vessels, comprising a pair of blades adapted to be turned to either side and also opened out one from the other, or closed together, in combination with means for actuating the same by any suitable motive power and comprising a shank; a sleeve fitting said shank; a tiller loosely carried on but indirectly connected to said shank and sleeve; a screw carried in said tiller; a driving wheel and a traversing nut cooperating with said screw; and means for controlling said tiller from any desired position on the vessel, substantially as described.

5. In ships' rudders, the combination of a pair of rudder blades; a shank A' and sleeve B' on which said blades are pivoted; a bushing C for pivotally supporting said shank and sleeve; a tiller; and pivoting connections between said tiller and said shank and sleeve by which said blades may be closed to act as a rudder when going ahead; and may be opened to an obtuse angle to act as deflectors for the displaced water to send the ship astern, substantially as described.

6. In ships' rudders, the combination of a pair of rudder blades; a shank A' provided with a fin A'; a sleeve B' provided with a fin B'; means for rigidly securing said blades to said fins; a bushing C for pivotally supporting said shank and sleeve; a tiller; and pivoting connections comprising a screw and nut between said tiller and said sleeve by which said blades may be closed to act as a rudder when going ahead; and may be opened to an obtuse angle to act as deflectors for the displaced water to send the ship astern, substantially as described.

In testimony wherof I have signed my name to this specification in the presence of two subscribing witnesses.

JOHAN PETER HENMELUND.
